STEAM TRAP.

APPLICATION FILED MAR. 18, 1903.

NO MODEL.

UNITED STATES PATENT OFFICE.

JOHN G. MORGAN AND WILLIAM BLETSO, OF YOUNGSTOWN, OHIO.

STEAM-TRAP.

SPECIFICATION forming part of Letters Patent No. 739,696, dated September 22, 1903.

Application filed March 18, 1903. Serial No. 148,377. (No model.)

To all whom it may concern:

Be it known that we, JOHN GRIFFITH MORGAN and WILLIAM BLETSO, citizens of the United States, and residents of Youngstown, 5 in the county of Mahoning and State of Ohio, have invented a new and Improved Steam-Trap, of which the following is a full, clear, and exact description.

The object of the invention is to provide a 10 new and improved steam-trap which is simple and durable in construction, very effective in operation, completely balanced, and arranged to insure a proper working of the trap and discharge of the water of condensation 15 under any pressure of the steam entering the trap.

The invention consists of novel features and parts and combinations of the same, as will be more fully described hereinafter and 20 then pointed out in the claims.

A practical embodiment of the invention is represented in the accompanying drawings, forming a part of this specification, in which similar characters of reference indicate corresponding parts in all the views.

Figure 1 is a longitudinal sectional elevation of the improvement on the line 1 1 of Fig. 2. Fig. 2 is a transverse section of the same on the line 2 2 of Fig. 1. Fig. 3 is a side 30 elevation of the improvement. Fig. 4 is an enlarged plan view of the hollow pivot for the vessel to rock on, and Fig. 5 is a similar view of the sleeve of the vessel.

On a suitably-constructed stand A is set- 35 cured by set-screws B a transversely-extending pivot C, made hollow and formed at or near its middle with a transverse partition C' (see Fig. 2) to form a steam-inlet C² at one end of the pivot C and a water discharge or 40 outlet C³ at the other end of the said pivot. The inner end of the steam-inlet C² is adapted to connect by a port a in the wall of the pivot C with a port b, formed in the wall of a sleeve or bushing D', secured in the transverse partition D² of a vessel D, preferably made cylindrical and divided by the said partition D² into a receiving-compartment D³ and a counterweight-compartment D⁴, containing a counterweight E, as plainly shown in Fig. 1. The 45 port b in the sleeve D' leads to a passage or port c, opening into the compartment D³ near the top of the partition D², so that steam can

pass from the steam-inlet C² through the registering ports a, b, and c into the said compartment D³ to condense therein.

The inner end of the water discharge or outlet C³ is adapted to connect by a port d in the wall of the pivot C with a port e, formed in the sleeve D' and leading to a port f, extending upwardly in the partition D², and 60 from the upper end of this port f extends a pipe F, secured to the partition D² and extending downwardly and forwardly in the compartment D³ to within a short distance of the bottom thereof at the outer end of the 65 said compartment, as plainly indicated in Fig. 1.

The ports a and d are so arranged (see Fig. 4) that when one is in register with its sleeve- 70 port b or e then the other port is cut off from its sleeve-port, and vice versa.

When the trap is emptied, as shown in Figs. 1, 2, and 3, then the counterweight E holds the vessel D normally in a horizontal position with the compartment D⁴ resting on a 75 set-screw G, carried by the stand A, and when the vessel is in this position the ports a and b are connected with each other, while the ports d and e are out of register. Now steam can pass from the steam-inlet C² by way of 80 the registering ports a, b, and c into the compartment D³ to fill the same with water of condensation, and when sufficient water has accumulated in the compartment to overbalance the counterweight E then the vessel 85 D rocks on its pivot C until the forward end of the compartment D³ abuts against the set-screw G', carried by the stand A. (See dotted lines, Fig. 3.) Now when this takes place the port b becomes disconnected from the 90 port a, while the port e moves in register with the port d, and consequently the water contained in the compartment D³ is now forced out of the latter by the pressure of the steam entrapped in this compartment through the 95 pipe F, registering ports f, e, and d, and water-outlet C³ to a suitable place of discharge. As soon as the water is discharged from the compartment D³ the vessel is caused to rock back to its normal position by the action of 100 the counterweight E, and consequently the port e is again disconnected from the port d, while the port b can move to register with the port a, and steam can now pass again into

the compartment D³ and condense therein. The ports b and c can be made to remain open or closed when the trap is discharging.

The above-described operation is then repeated—that is, the vessel D is alternately rocked into a discharge position for discharging the water of condensation from the compartment D³ and into a receiving or horizontal position for the steam to pass into the said compartment to be condensed therein.

In order to prevent leakage, the vessel D is provided with suitable stuffing-boxes H, engaging the pivot C at the ends of the sleeve D', and in order to prevent lateral shifting of the vessel D on the pivot set-screws I are provided, screwing in the vessel through openings in the sleeve D' to engage annular grooves C⁴ in the pivot C, as plainly shown in Fig. 4. Plugs J screw in the partition D² from the top of the vessel into the ports c and f to allow of cleansing the same in case it becomes necessary to do so.

From the foregoing it will be seen that the trap is completely automatic in its operation and is not liable to easily get out of order, as no valves, springs, or the like are employed.

Having thus described our invention, we claim as new and desire to secure by Letters Patent—

3. A steam-trap, comprising a vessel having a partition for forming a receiving-compartment and a counterbalancing-compartment, a hollow pivot extending through said partition and provided with a steam-inlet and a water-outlet, and means for alternately connecting the receiving-compartment with the steam-inlet and the water-outlet, as set forth.

4. A steam-trap, comprising a support, a vessel having a transverse partition dividing said vessel into a receiving-compartment and a counterweight-compartment, the said partition being formed with ports communicating with the receiving-compartment, a sleeve secured in the transverse partition and provided with ports communicating with the ports in the partition, and a hollow pivot secured to the said support and extending through the said sleeve in the partition, the said pivot having a transverse partition at its middle to form a steam-inlet at one end of the pivot and a water-outlet at the other end, the said pivot having ports adapted to register alternately with the ports of the sleeve, as set forth.

5. A steam-trap provided with a counterbalanced vessel, a pivot for the vessel to turn on, from a receiving position into a discharge position and vice versa, the said pivot hav-

ing an inlet for the steam and an outlet for the water, and the vessel being provided with a steam-inlet port and a water-outlet port, registering with the said steam-inlet and the said water-outlet in the pivot, a pipe extending into the vessel and connected with the water-outlet port, and means carried by the vessel and engaging the pivot to prevent lateral shifting of the vessel on the pivot, as set forth.

4. A steam-trap provided with a vessel having a transverse partition for forming a receiving-compartment and a counterbalancing-compartment containing a weight, a fixed pivot extending through the said partition and provided with a steam-inlet and a water-outlet, adapted to register alternately with ports formed in the said partition, the steam-inlet port opening into the said vessel, and a pipe connected with the water-outlet port and extending in an inclined position in the said receiving-compartment, as set forth.

5. A steam-trap provided with a vessel having a transverse partition for forming a receiving-compartment and a counterbalancing-compartment containing a weight, a fixed pivot extending through the said partition and provided with a steam-inlet and a water-outlet, adapted to register alternately with ports formed in the said partition, the steam-inlet port opening into the said vessel, a pipe connected with the water-outlet port and extending in an inclined position in the said receiving-compartment, and means, substantially as described, for limiting the rocking motion of the said vessel, as set forth.

6. A steam-trap provided with a vessel having a transverse partition for forming a receiving-compartment and a counterbalancing-compartment containing a weight, a fixed pivot extending through the said partition and provided with a steam-inlet and a water-outlet, adapted to register alternately with ports formed in the said partition, the steam-inlet port extending into the said vessel, a pipe connected with the water-outlet port and extending in an inclined position in the said receiving-compartment, and means for holding the vessel against transverse movement on its pivot, as set forth.

In testimony whereof we have signed our names to this specification in the presence of two subscribing witnesses.

JOHN G. MORGAN.
WILLIAM BLETSO.
